UNITED STATES PATENT OFFICE.

CLAUD E. HARLAN, OF WATSONVILLE, CALIFORNIA, ASSIGNOR OF ONE-HALF TO
WILLIAM H. AMES, OF WATSONVILLE, CALIFORNIA.

SPARKING INDICATOR.

1,140,816.

Specification of Letters Patent.

Patented May 25, 1915.

Application filed September 15, 1914. Serial No. 861,812.

To all whom it may concern:

Be it known that I, CLAUD E. HARLAN, a citizen of the United States, residing at Watsonville, in the county of Santa Cruz and State of California, have invented new and useful Improvements in Sparking Indicators, of which the following is a specification.

This invention relates to a sparking indicator.

10 The object of the present invention is to provide a simple portable testing instrument for locating trouble in the ignition system of internal combustion engines, for instance, to determine whether the trouble is caused by a 15 fouled plug, a short circuit in the wiring connections, punctured insulation, magneto trouble, etc.

Further objects and advantages will appear hereinafter.

20 The invention consists of the parts and the combination and construction of parts as hereinafter more fully described and claimed, having reference to the accompanying drawings, in which—

25 Figure 1 is a front view of the testing instrument. Fig. 2 is a cross section on line 2—2, Fig. 1. Fig. 3 is a similar cross section showing a modification in the construction of the spark plugs. Fig. 4 is a diagrammatic view showing the instrument connected for testing. Fig. 5 is a diagrammatic view showing a modified form of construction.

30 More specifically described, the instrument comprises a cast metal casing A, in which is formed an air tight compression chamber 2 to which air may be admitted through a check valve 3 and registered by a pressure gage 4. The casing is otherwise provided 35 with a threaded opening 5 into which spark plugs, hereinafter called, "testing plugs" are screwed. The casing is also provided with a pair of glass covered openings 7, through which the terminals of the testing 40 plugs are visible.

45 The testing plugs employed in the instrument are preferably constructed as shown in Fig. 1. That is, each plug consists of two separate insulated terminals 8—9, which are independently secured by bushings 10—11. This construction permits insulation against high tension currents, such as are now most commonly used, and also prevents short circuiting between the plug and casing, as no ground connection is made with same.

The modified form shown in Fig. 3 is very similar, with the exception that the two terminals 8^a and 9^a are mounted in the same insulator.

50 In operation, referring to Fig. 4 which represents a two cylinder unit, the test is made as follows: The secondary wires 12—13 of the magneto are first disconnected with their respective engine plugs 14—15 and are then connected with terminals 8 on the instrument testing plugs. Terminals 9 of the testing plugs are then connected by wires 16—17 with the engine plugs 14—15 and these are in turn grounded by wire 18 in the usual manner. The engine can now be started and is preferably made to run at a comparatively slow speed while the test is being conducted. Air is now admitted into chamber 2 from any suitable source, or forced in by pump 19 until the pressure within the 75 chamber is brought to correspond approximately, or to a point somewhat above the maximum pressure in the engine cylinder under full compression. If the spark passes through the testing plugs regularly and 80 properly under such conditions, it may be quite safely assumed that the spark is also jumping across the terminals of the plugs in the engine. If, however, the sparks on one of the testing plugs, or both, begin to fail 85 as the pressure increases in chamber 2, it shows immediately that something is wrong with the ignition system. For instance, leakage may occur in the wiring or connections, or the contact points in the distributor of the 90 magneto may be set too far apart or partly corroded, or a short circuit in the connections may be found. The conductivity of air or vapor decreases with an increase in pressure. It can therefore be seen that if 95 any connection between the engine plugs and magneto are leaking or otherwise defective, that as the pressure in chamber 2 is increased this defect will immediately be indicated, as the resistance caused by the pressure within 100 the chamber will be sufficient to prevent the current or spark from jumping the gap between the terminals of the testing plug.

105 The construction of the testing instrument here shown permits the ignition system of any internal combustion engine to be tested while the engine is running, and also eliminates the necessity of removing the engine plugs while the test is being made. The test can be made at various engine speeds; 110

this being an important feature of the present invention, as the current output of some generators or magnetos vary greatly with change in speed.

5 In Fig. 5 a slight modification is shown in which casing A is constructed of a pair of cross shaped pipe fittings 24 and 25. These fittings are connected together, but insulated from each other, by a fiber nipple 26. This connects the internal chambers in the fittings and permits the air to become equally distributed. Any ordinary spark plug may be used as a testing plug in this instance, as wires 16 and 17 may be grounded on each 15 fitting by reason of the insulation 26.

Having thus described my invention what I claim as desire to secure by Letters Patent is—

1. A sparking indicator comprising a casing having a chamber formed therein, a spark plug mounted in the casing and extending into said chamber, said plug having two separated terminals insulated from each other and the casing, means for admitting air under pressure into said chamber, and a gage for registering said pressure.

2. A sparking indicator comprising a casing having a chamber formed therein, a spark plug mounted in the casing and extending into said chamber, said plug having two separated terminals insulated from each other and the casing, openings formed in the casing having transparent closures mounted therein, said openings being in line 35 with the terminals of the spark plugs, means for admitting air under pressure into said chamber, and a gage for registering said pressure.

3. A sparking indicator comprising a casing having a chamber formed therein, a spark plug mounted in the casing and extending into said chamber, said plug having two separated terminals insulated from each other and the casing, openings formed in the casing having transparent closures mounted therein, said openings being in line 45 with the terminals of the spark plugs, a check valve for admitting air under pressure into the chamber, and a gage for registering said pressure.

4. The combination with the spark plugs in an internal combustion engine, and the current supply for same, of testing spark

plugs interposed on the circuit between the engine plugs and current supply, a casing 55 having a chamber formed therein in which the testing plugs are mounted, and in which the terminals of same may be observed, and means for forcing air under pressure into said chamber.

5. The combination with the spark plugs in an internal combustion engine, and the current supply for same, of testing spark plugs interposed on the circuit between the engine plugs and current supply, a casing 65 having a chamber formed therein in which the testing plugs are mounted, and in which the terminals of same may be observed, means for forcing air under pressure into said chamber, and a gage for registering same pressure.

6. The combination with the spark plugs in an internal combustion engine, and the current supply for same, of testing spark plugs interposed on the circuit between 75 the engine plugs and current supply, a receptacle having a chamber formed therein in which the testing plugs are mounted and in which the terminals of same may be observed, said receptacle consisting of a plurality of units insulated from each other, there being one unit for each testing plug, and means for forcing air under pressure into the several units.

7. The combination with the spark plugs 85 in an internal combustion engine, and the current supply for same, of testing spark plugs interposed on the circuit between the engine plugs and current supply, a receptacle having a chamber formed therein 90 in which the testing plugs are mounted and in which the terminals of same may be observed, said receptacle consisting of a plurality of units connected together by insulated nipples, and means for forcing air under pressure into connected chambers of the several units, and a pressure gage for registering said pressure.

In testimony whereof I have hereunto set my hand in the presence of two subscribing 100 witnesses.

CLAUDE HARLAN.
